SECTIONAL BOILER

Valentine Gerich, New York, N. Y.

Application August 20, 1940, Serial No. 353,323

3 Claims. (Cl. 122—225)

This invention relates to an improvement in sectional cast iron low-pressure steam boilers and hot water heaters.

A salient feature of this invention, is the instant installation of any number of intermediate sections that may be secured by stay-rods to the front header and rear sections, to suit the required horsepower and space available, either in the single, duplex or multiple type of steam or hot water boilers.

Another salient feature of this invention, is the design of a tubular shell boiler, having five levels of large and small fire flue passages arranged in a very compact manner, each level of fire flues being connected in the front header and rear sections by means of by-passages set at about 45 degrees, whereby the heat is concentrated for greater heating efficiency in the larger fire flues of the intermediate sections.

Another salient feature of this invention, is the caulking seams that provide sealing means between all of the sections, and the fire-flue passages. The space between each section is only one-eighth of an inch, into which soot will eventually seal and close up and thus solidifying the entire assembled sections, and together with vertical and horizontal caulking seams in between each of the fire-flue passages, provide greater fire and heating efficiency.

These diagonal by-passages are side feeders from small fire-flues to the central vertical formation of larger fire-flues leading from the fire-box or fire-pot to the smoke stack at rear end section, the smaller fire-flues being staggered in between the circular wall portions of the larger fire-flues so as to make more compact the complete fire and heating efficiency of the each boiler unit, either single, duplex or in the multiple type.

Another salient feature of this invention, is the interchangeable and convertible means provided in the fire-boxes for burning either coal, pulverized coal, fuel oil or gas.

Another salient feature of this invention, is the adaptability of providing the interconnecting sections with their fire-flues and by-passages for a duplex or multiple type boiler of greater horsepower for factory and large buildings, or for only a single fire-box boiler of a small horsepower for individual homes and small buildings.

Other features of the invention will appear as the description proceeds in the following specification, accompanied by the annexed drawings, in which

Figure 1 is a front elevation of the sectional

duplex boiler of this invention, on about a scale of $\frac{3}{4}$ " to the foot, thus providing a duplex boiler 5 feet wide by 6 feet 6 inches high.

Figure 2 is a side elevation of the same sectional boiler.

Figure 3 is a face view of the front header section showing the fire-flues in their zig-zag connections on line 3—3 of Figures 2 and 7.

Figure 4 is a cross-sectional of one of the intermediate sections, with the water omitted, taken on line 4—4 of Figure 5.

Figure 5 is a sectional view on line 5—5 of Figure 4 with the water, caulking liners and radius stay-rods omitted.

Figure 6 is an enlarged detail sectional view of one of the interconnecting sleeves in between each individual section.

Figure 7 is an enlarged longitudinal section following each zig-zag fire-flue on each of the five levels, taken on the zig-zag line 7—7 of Figure 3.

Figure 8 is a fragmentary view of the front fire-box showing the use of an oil burner in place of coal.

Figure 9 is a front elevational view of the small single fire-box boiler.

Figure 10 shows a detail of a double threaded bolt which may be optionally placed at flat open surfaces during the moulding and casting of each section which when cooled secures bolt in a fixed position therein.

Figure 11 is a much preferred modified form of coupling each section together in place of the sleeve tubes 11 and 12.

Referring to the drawings, the numerals 1 and 2 indicates the front header sections and 3 and 4 the rear header or end sections of the boiler, having intermediate sections 5, 6, 7, 8, 9 and 10 interconnecting therebetween by means of water and steam circulating sleeve members 11 and 12, respectively, which are firmly wedged into and secured into openings of each of the connected sections by means of threaded ends of radius stay-rods 13 and locking nuts 14, which also firmly secure the asbestos-like liners 15 into their round caulking seams 16 and 17, shown clearly in the enlarged sectional view of Figure 7.

All of the sections 1 to 10 are closely positioned so the space in between the sections at the caulking seams 16 and 17 is filled up with soot, adjacent the asbestos-like liners 15 thereby providing smooth-like flues in the large fire-boxes 20 and 21, the larger fire-flues 21, 22, 28 and 29 and the smaller by-passages and fire-

flues 23, 24, 25, 26, 30, 31, 32 and 33, all of which lead to the rear stack flue 34.

The fire boxes 20 and 21 are tubular in shape and are provided with grates G for coal burning, the grates being operated by a rod R and lever L, all of which is well known. The fire boxes are provided with an upper and lower doors 35 and 36, semi-circular in shape, as shown clearly in Figure 1, and have latches 37, hinges 38, bolts 39, sight holes 40, draft control 42, and a grater shaker GS on the fixed portion 43 having the latch locking arrangement 44.

Large and small doors 50 and 51 are provided for each of the larger and smaller fire-flues, these doors having similar parts as those described on doors 35 and 36 and are primed accordingly. Water gauge 54, blow-off cocks 55, clean out plugs 56, brass wash out and clean out plugs 58 and 59 for the water space and the steam sleeves 11 and 12, all of which are provided similar to all boilers.

The front section 1 has door openings in direct alignment with each of the fire-flues, and the rear section 3 has the stack opening 60 and rear clean out opening 61 and door 62 to clean out the combusting chamber CC 20 and 21. The adjacent interconnectable sections 1, 2, 3 and 4 are provided with the connecting by-passages as indicated by the arrows A in Figure 7, and by the shaded passages P in Figure 3.

It is to be noted that the longitudinal walled water spaces of each section in between each of the fire-flues, as shown in Figure 7, is for the purpose of illustrating the continuous fire-heat wave passages as taken on the zig-zag line 7-7 in Figure 3. The exact water space, however, surrounding each fire-flue is shown clearly in Figures 3, 4 and 5. The fire-flues have been arranged so that a more efficient boiler per horsepower for a low pressure is provided in the least head room space permissible for the installation of either the larger duplex or smaller singular type of sectional boilers.

The fire-box of each tubular passage 20 and 21, either in the single or duplex form, is provided with a rear fire wall 82, thus providing the separation of the combustion chamber CC from the ash pit of the front fire-box when used for coal. It may be retained for the oil and gas blowers and pulverize coal burners, if so desired.

Each section is provided with positioning lugs or projections 70 adapted for the installation work onto the floor base B comprising a rigid frame of cross and longitudinal members 74 and 75. The members 75 have a recessed portion 76 through which a suitable bar may be inserted underneath each section in order to pry same into proper position for each section to be drawn securely together with the interconnecting water and steam sleeve-tubes 11 and 12 by the radius stay-rods 13 and nuts 14. After the asbestos-like liners 15 are inserted in the caulking seams 16 and 17, the liners 15 are inserted on each side of the vertical seam 17. At the rear section a condensation return pipe 90 and a blow-off cock 91 is provided, also a safety blow-off valve 92 is provided for steam boilers and for hot-water heater boilers a thermostat 100 is used.

When it is desired to change the means of firing the boiler, for example, from the coal burner, as shown in Figure 7, to the oil burner OB as shown in Figure 8, the rods R and grates G are removed from the bearer sockets 80, after which the fire-bricks 81 are removed and through the opening thereby provided, an oil burner nozzle

is inserted for burning oil into the fire-box. This applies also to installing pulverized coal burners, but for a gas burner the grates G remain in the normal position as shown in Figure 7 for burning coal.

Boilers of more or less capacity, will vary in size, and therefore, the front and rear end sections with the intermediate sections will have corresponding smaller or larger fire-flues and interconnecting sleeves accordingly.

In Figure 9 a singular type of a sectional boiler is shown, where only one fire-box and fire-flues are provided. This singular type is similar to the duplex type boiler hereinbefore described, and similar parts will be primed accordingly. This singular type boiler is adaptable for a small size plant for hot water and steam heating, in which the thermostat 100 or the steam gauge 101 is provided, respectively.

In Figure 11, a much preferred modification of the sections 1 to 10, inclusive, is shown whereby the interlocking sleeve members 11 and 12 are eliminated, and in place thereof, female and male connections are provided integrally in the face portions of the casting of each section, such as for example, by bosses 105 that fits into the countersunk openings 106 when the sections are drawn together by the radius stay-rods 13 and lock nuts 14.

Headers 110 are for the steam chambers SC, in which the water line is about 4 inches above the uppermost fire-flues 22 and 29.

For circulating hot-water, there is no water line, and the headers for the hot-water supply line may be suitably placed as usually done.

Doors 36 and 35 are for the stoking of coal and ash removal, respectively, and a clean-out door 115 and draft-check 116 are provided at the rear section on the underside of the smoke stack 111, as noted in Figure 2.

It is to be understood that any part of this invention as hereinbefore described and shown in the drawings, may be altered to improve the efficiency of the boilers, providing same comes within the spirit of this invention and the appended claims.

Having thus described my invention what I claim as new and desire to secure by Letters Patent, is as follows:

1. In a sectional steam boiler or hot-water heater of the character described, the combination of front and rear sections having interconnecting sections therebetween, each of said sections provided with water and steam sleeve-tube members providing circulating means between each of said sections, said sections being provided with openings forming double fire-boxes and combustion chambers and longitudinally small size and large size fire flues spaced vertically above the fire-boxes and combustion chambers, and by-passages connecting some of the small size fire-flues with the fire-boxes and combustion chambers and other by-passages connecting the small size fire-flues with the large size fire-flues all of which form a passage leading to the smoke stack in the rear section, the lower part of the rear section being provided with a clean-out hole and door that permits access to the passage, the front header section being provided with clean-out openings and doors for each of said fire-flues, each of said fire-boxes being provided with a pair of semi-circular doors in the front header section, one of which is for a fuel feeder and the other of which is for an ash pit, the sections being provided with caulking seams, asbestos-

like liners inserted in between said seams, suitably spaced radius stay-rods extending through the sections, said sections and interconnecting sleeve-tube members being adaptable to be drawn together by said radius stay-rods, whereby all of said fire-boxes, fire-flues and their by-passages are rigidly secured in alignment with each other and said asbestos-like liners secured in between said caulking seams, thus sealing each of said fire-flues.

2. In a sectional steam boiler or hot-water heater of the character described, the combination of front and rear sections having interconnecting sections therebetween, each of said sections provided with water and steam connections providing circulating means between each of said sections, said sections being provided with tubular openings forming double fire-boxes and combustion chambers and longitudinally extending small size and large size fire-flues spaced vertically above the fire-boxes and combustion chambers, and by-passages connecting some of the small size fire-flues with the fire-boxes and combustion chambers and other by-passages connecting the small size fire-flues with the large size fire-flues all of which form a passage leading to the smoke stack in the rear section, the lower part of the rear section being provided with a clean-out hole and door that permits access to the passage, the front header section being provided with clean-out openings and doors for each of said fire-flues, each of said fire-boxes being provided with a pair of doors in the front header section, one of which is for a fuel feeder and the other of which is for access to the ash pit, all of said sections being provided with caulking seams, asbestos-like liners inserted in between said seams, suitably spaced radius stay-rods extending through all of said sections, said sections and water and steam connections being adaptable to be drawn together by said radius stay-rods, whereby all of said fire-boxes, fire-flues and their by-passages are rigidly secured in alignment with

each other and said asbestos-like liners secured in between said caulking seams thus sealing each of said fire-flues.

3. In a sectional steam boiler or hot-water heater of the character described, the combination of front and rear sections having interconnecting sections therebetween, each of said sections provided with water and steam connections providing circulating means between each of said fire-flues.
  - 5 10 15 20 25 30 35 40
5. In a sectional steam boiler or hot-water heater of the character described, the combination of front and rear sections having interconnecting sections therebetween, each of said sections provided with water and steam connections providing circulating means between each of said sections, said interconnecting sections being provided with tubular openings forming a fire-box and combustion chamber and longitudinally extending small size and large size fire-flues spaced vertically above the fire-box and combustion chamber, and by-passages connecting some of the small size fire-flues with the fire-boxes and combustion chambers and other by-passages connecting some of the small size fire-flues with the large size fire-flues all of which form a passage leading to the smoke stack in the rear section, the lower part of the rear section being provided with a clean-out hole and door that permits access to the passage, the front header section being provided with clean-out openings and doors for each of said fire-flues, said fire-box being provided with a pair of doors in the front header section, one of which is for feeding the fuel therein and the other for the removal of the ashes from the pit therein, all of said sections being provided with caulking seams, asbestos-like liners inserted in between said seams, suitably spaced radius stay-rods extending through said sections, said sections and connections for water and steam circulating means being adaptable to be drawn together by said radius stay-rods, whereby all of said openings forming the fire-box, combustion chamber, fire-flues and their by-passages are rigidly secured in alignment with each other and said asbestos-like liners secured in between said caulking seams thus sealing each of said fire-flues.

VALENTINE GERICH.
